UNITED STATES PATENT OFFICE.

HARRY TYLDESLEY, OF CENTRAL CITY, KENTUCKY, ASSIGNOR OF ONE-THIRD TO THOMAS TYLDESLEY AND ONE-THIRD TO MILTON P. CREEL, OF CENTRAL CITY, KENTUCKY.

DRILLING APPLIANCE.

No. 870,701.

Specification of Letters Patent.

Patented Nov. 12, 1907.

Application filed March 1, 1907. Serial No. 360,048.

To all whom it may concern:

Be it known that I, HARRY TYLDESLEY, a citizen of the United States, residing at Central City, in the county of Muhlenberg and State of Kentucky, have 5 invented certain new and useful Improvements in Drilling Appliances, of which the following is a specification.

This invention is a drilling-appliance, and more particularly a drill and a coöperating guide or templet for 10 producing a square hole.

The object of the invention is to provide an appliance of this kind which can be readily fitted to an ordinary drilling machine, and also an adjustable guide or templet.

15 In the accompanying drawing, Figure 1 is a front elevation showing the application of the invention. Fig. 2 is a side elevation. Fig. 3 is a horizontal section on the line 3—3 of Fig. 1. Fig. 4 is a horizontal section on the line 4—4 of Fig. 1. Fig. 5 is a transverse section on the line 5—5 of Fig. 4. Fig. 6 is a plan view of the parts constituting the drill-guide or templet showing them separated.

20 Referring specifically to the drawing, 10 denotes the column of a drilling machine and 11 one of the arms thereof having a bearing head 12 for the drill-spindle 13. The table on which the work to be drilled is placed is indicated at 14. The drill-spindle is fitted with a chuck 15 in which the drill 16 is held. The cross-section of the cutting end 17 of the drill is that 25 of an equilateral triangle, and above this the drill is twisted to form a spiral groove 18 for the discharge of the chips.

25 The guide or templet for the drill comprises a pair of rectangular plates 19 and 20, respectively, each of which is recessed in such a manner that when the plates are placed together with the recesses opposite each other a square hole 21 is formed as shown in Fig. 4 in which hole the cutting part 17 of the drill works. The plates 19 and 20 are mounted in a frame 40 which comprises two parts indicated at 22 and 23, respectively. The part 22 comprises a plate having two parallel arms 24, the space between which forms a recess in which the plates 19 and 20 fit and are secured by a tongue and groove joint. The part 23 is a 45 plate which abuts against the plate 19 when the latter

is in position between the arms 24, and has parallel arms 25 between which the arms 24 extend and are secured by a tongue and groove joint.

The drill-guide or templet herein described is placed on top of the work 26 to be drilled and is firmly held 50 thereon by standards 27 rising from the plates 22 and 23 and secured to a collar 28 clamped to the head 12. The collar is in two parts which embrace the head and have at their abutting ends flanges 29 whereby they are bolted together as at 30 and thus clamped to the 55 head. The collar has projecting lugs 31 provided with vertical openings through which the standards 27 extend and in which they are adjustably fastened by set-screws 32. This construction permits the drill-guide to be adjusted vertically according to the thickness 60 of the work 26 or the position of the table 14.

In use, the drill-guide will be placed on the work to be drilled and firmly secured thereon in the manner heretofore stated, with the hole 21 directly over that portion of the work where the hole is to be drilled. 65 The drill is caused to enter the material through the hole 21 whereby it is guided to form a square hole. Various sized holes can be drilled by changing the drill and the plates 19 and 20, and after the hole is started the plates can be removed, the hole already 70 drilled then serving as a guide. The plates 19 and 20 can be readily removed for this purpose by separating the plates 22 and 23 as shown in Fig. 6 and disconnecting the collar sections.

75 I claim:—

1. The combination with a relatively fixed drill head through which the drill spindle extends, of a collar clamped around said head and having projecting lugs, a drill guide adapted to rest upon the work, and standards fixed to the guide and extending upwardly therefrom and 80 through the lugs, and adjustably secured therein.

2. The combination with a fixed drill head, of a drill guide comprising a frame of separable parts, each part having a standard projecting upwardly therefrom beside the drill and fixed to the drill head, and opposite plates 85 removably held in the frame and having a guide opening therebetween through which the drill works.

In testimony whereof I affix my signature, in presence of two witnesses.

HARRY TYLDESLEY.
